UNITED STATES PATENT OFFICE

ARTHUR M. JOHNSON, OF HIGHLAND PARK, ILLINOIS

ROTATABLE GRINDING OR HONING DEVICE

Application filed February 4, 1928. Serial No. 251,830.

This invention relates to rotatable grinding or honing devices and particularly to devices of the character adapted for use in honing or surfacing the inner face or walls of engine cylinders or the like.

One object of the present invention is to provide means for varying the diametrical dimension of the grinding tool by a novel construction and arrangement whereby a plurality of annularly spaced grinding stones are moved radially and uniformly with respect to the center of rotation of the tool.

Another object of the invention is to provide means whereby, in the operation of the device, the stones are uniformly supported throughout their entire length regardless of the degree of contraction or expansion to which the tool may be adjusted.

Another object of the invention is to provide a hone body of novel construction on which the stones and stone actuating means may be conveniently mounted in a manner to be readily assembled and disassembled, and on which a portion of the stone actuating means is formed, and having also a novel construction whereby the stones are secured against longitudinal movement with respect to the hone body.

Another object of the invention is to provide suitable driving means for rotating the honing tool, the said means embodying a novel construction and arrangement for actuating and controlling the tool expanding or stone adjusting means.

Another object of the invention is to provide a novel coupling means for readily connecting and disconnecting the tool to and from its driving spindle.

Another object of the invention is to provide a novel construction and arrangement, whereby the actuation of the tool expansion controlling means may be definitely determined.

A further object of the invention is to provide a device of the character described wherein a suitable degree of flexibility between the tool and its driving means may be obtained to facilitate the centering of the tool within an engine cylinder or the like.

A still further object of the invention is

to provide an efficient, practicable and durable cylinder hone, and to improve devices of this character in sundry details herein-after described and particularly pointed out in the appended claims.

One embodiment of the invention is shown for illustrative purposes in the accompanying drawings, in which

Fig. 1 is a side elevational view of a cylinder grinding device embodying my invention.

Fig. 2 is an enlarged side elevational view of the honing tool shown in Fig. 1.

Fig. 3 is a longitudinal sectional elevation of the honing tool taken as indicated by the line 3—3 of Fig. 2.

Fig. 4 is a transverse sectional view taken on the line 4—4 of Fig. 3.

Fig. 5 is a transverse sectional view taken on the line 5—5 of Fig. 3 and illustrating the manner of actuating the coupling means for connecting the grinding tool and spindle.

Fig. 6 is a bottom plan or lower end view of the grinding tool illustrated in Figs. 2 and 3.

Fig. 7 is a transverse sectional plan view taken on the line 7—7 of Fig. 3, illustrating the construction of the coupling means.

Fig. 8 is a fragmentary elevational view of the parts shown in Fig. 7.

Fig. 9 is a perspective view of one of the grinding stone adjusting bars.

Fig. 10 is a central sectional elevation of the driving means and the construction and arrangement of means for actuating and controlling the tool expanding or stone adjusting means.

Fig. 11 is a side elevational view of a portion of Fig. 10 having parts thereof broken away to illustrate, more clearly, the construction of portions of the tool expanding or adjusting means.

Fig. 12 is a transverse sectional plan view taken on the line 12—12 of Fig. 10.

Fig. 13 is a transverse sectional plan view taken on the line 13—13 of Fig. 10.

Fig. 14 is a transverse sectional plan view taken on the line 14—14 of Fig. 10.

Fig. 15 is a fragmentary sectional elevation taken on the line 15—15 of Fig. 14.

Referring to the drawings, and particularly to Figs. 1 to 9 inclusive thereof, the present invention includes a rotatable longitudinally reciprocable grinding tool or cylinder hone designated as a whole by the numeral 20, and comprising a base or body member or portion 21 having a plurality of longitudinally disposed radially movable abrading stones 22 mounted therein and annularly spaced around the periphery of said body members.

For mounting the abrading stones 22 in the body member 21 in a manner to permit of radial movement with respect thereto, 15 the stones are suitably secured, preferably rigidly, in stone holders 23 adapted to be positioned in longitudinal grooves 24 formed in the periphery of the central portion 21a of the body member 21 and extending longitudinally with respect thereto, the 20 said holders being secured against longitudinal movement with respect to the body member by means of shoulders 25, shown, in the present instance, as provided by radially slotted annular flanges 26 formed integrally with and adjacent the ends of the body member 21.

For moving the abrading stones 22 and 30 stone holders 23 outwardly with respect to the body member 21, when it is desired to expand the diametrical dimension of the tool 20 for the purpose of maintaining the abrading stones 22 in contact with the surface to be operated upon, as, for example, 35 the inner surface of an engine cylinder or the like, the body member 21 is provided, preferably adjacent its opposite ends, with cams 27 inclined at an angle to the center line of the body member 21, the inclined 40 planes of the cams extending in parallel relation to each other. The cams 27 of the illustrative embodiment of the invention are shown in the drawings as formed integrally with the body member 21 with their inclined 45 surfaces extending annularly around the body member and forming, in effect, a truncated cone construction adjacent opposite ends of the body member. It will be observed that by such a construction, the cams 50 55 27 may be accurately formed by turning down the body member 21, thereby providing annular grooves between the central portion 21a of the body member and the annular flanges 26 adjacent the ends of the body member.

Formed in the central portion 21a of the body member 21 and extending longitudinally thereof are a plurality of annularly spaced 60 grooves or channels 28 positioned in the radial plane of the holders 23 and channels 24, the channel 28 being preferably relatively narrower than the channel 24. Positioned in the channels 28 in a manner to be moved longitudinally and laterally therein are a plurality of abrading stone adjusting bars 29

comprising a relatively thin central portion adapted to be positioned in the groove or channel 28 between the body member 21 and stone holders 23 and having inclined cam surfaces or portions 30 formed adjacent their opposite ends and adapted to engage and cooperate with the respective cams 27 formed adjacent the ends of the body member 21. It will be observed by reference particularly to Fig. 3, that when the abrading stones 22 are in their retracted position and the diametrical dimension of the tool 20 reduced to a minimum, the construction and arrangement of the adjusting bars 29 and cam portions 30 are such that the stone holders 23 are completely supported throughout their entire length by said adjusting bars and their integrally formed cam portions 30, thereby preventing any tilting or canting of the abrading stones 22 and holders 23 in their supporting grooves or channels by reason of any portion of the stone holders 23 extending beyond their supports, shown, in the present instance as the adjusting bars 29.

For moving the adjusting bars 29 longitudinally in their respective grooves 28, the bars are provided, adjacent one of their end portions, with transversely extending notches 31 adapted to receive the outer end portions of radially extending arms or fingers 32 comprising part of a spider member 33 having a centrally disposed hollow shank portion 34 slidably mounted in a centrally disposed longitudinally extending bore 35 formed in the body member 21, the said arms or fingers 32 extending through radially disposed slots 36 formed in the body member in a manner to permit the spider to be moved longitudinally thereof and secured against rotary movement with respect thereto.

Extending longitudinally through the hollow shank portion 34 and through the bore 35 and the relatively smaller bore 37 formed in the body member 21 is a longitudinally movable spider shifting rod 38, having secured to its outer or lower end, beyond the spider member 33, a spherically formed washer 39 by means of nuts 40 in a manner to cause the spider member 33 and radially extending arms or fingers 32 to be moved longitudinally of the body member 21 when the rod 38 is moved in an upwardly direction with respect to the body member 21, thereby causing the adjusting bars 29, through their connection with the arms 32, to be moved in the same direction and causing the cam faces 30 of the adjusting bars 29 to impinge the inclined surfaces of the cams 27 in a manner to cause the bars 29 to move laterally or radially with respect to the body member 21, thereby moving the stone holders 23 and stones 22 outwardly and radially with respect to the body member 21, thus increasing the diametrical dimension of the tool 20 for retaining the outer surface of the abrading stones 22 in en-

gagement with the surface or surfaces to be operated upon.

For moving the spider 33 and connected adjusting bars 29 in the opposite direction, a compression spring 41 is positioned in the bore 35 in a manner to operate between the inner end of the shank portion 34 of the spider 33 and a shoulder 42 formed in the body member 21 at one end of the bore 35, and it will be observed that as the spider member 33 and adjusting bars 29 are moved outwardly by the spring 41, the cam surfaces 30 of the bars 29 will follow the inclined surfaces of the cams 27 inwardly toward the center of the body member 21, thereby permitting the abrading stones 22 and stone holders 23 to be drawn inwardly toward the body member 21 by means of resilient flexible bands 43, shown in the present instance, as helical tension springs encompassing the pins or trunnions 44, the latter being preferably screw threaded into the opposite ends of the stone holders 23 and extending outwardly therefrom through radially disposed notches or slots 45 formed in the annular flanges 26 of the body member 21 adjacent the ends thereof, and the said notches at the lower or outer end of the body member forming a continuation of the slots 36, in which are positioned the arms or fingers 32 of the spider member 33.

For operating the grinding tool or hone 20, a rotatable longitudinally reciprocable hollow spindle 46 is secured at its lower end, by means of a releasable coupling to the body member 21 and at its upper end is provided with a coupling 47 having a tapered shank portion 48 adapted to be secured in a supporting member 49 connected with any suitable mechanism, not shown, for imparting a rotary and reciprocatory movement to the spindle, or, if desired, instead of reciprocating the spindle 46 and tool 20, the work to be operated upon may be reciprocated with respect to the tool, in which case, the mechanism to which the member 49 is connected may be constructed to impart only a rotary movement to the spindle and tool.

For securing the spindle 46 to the tool 20 in a manner to be readily connected thereto and disconnected therefrom, the body member 21 is provided adjacent its upper end with a relatively reduced portion 50 having a centrally disposed longitudinally extending bore or socket 51 formed therein adapted to receive the lower end of the spindle 46. The portion 50 is provided with a pair of diametrically and radially disposed vertically extending notches and slots 52 adapted to receive therein a pair of oppositely disposed radially extending pins or trunnions 53 secured to the opposite sides of the spindle 46 in a manner to cause the body portion to rotate with the spindle. Surrounding the portion 50 is a locking sleeve 54 secured against

longitudinal movement on the portion 50 by means of a pair of pins 55, shown in the present instance as machine screws, secured to diametrically opposite sides of the portion 50 and extending radially therefrom at an angle of substantially ninety degrees to the radial line of the notches or slots 52. The pins or screw heads 55 extend into horizontally disposed elongated openings or slots 56 formed in the sleeve 54 which permit of a limited rotary movement of the sleeve on the portion 50.

Formed in the sleeve 54 adjacent the lower end thereof is an annular recess or counterbore 57, see Figs. 3 and 5, adapted to receive a resilient tension member shown in the present instance as a coil spring 58 having one of its ends secured to the portion 50 of the body member 21, as indicated at 59 in Fig. 5, and its opposite end, under tension, to the sleeve 54, as indicated at 60. Thus, it will be seen that the spring 58 under tension holds the sleeve yieldingly against the pins or screw heads 55 at one end of the slots 56.

Formed in the sleeve 54 at substantially right angles to the slots 56 is a pair of oppositely disposed L-shaped slots 61, the vertical portions 62 of which may be brought into register with the slots or notches 52 by rotating the sleeve 54 against the action of the spring 58 to a point where the pins or screw heads 55 occupy a position in the opposite ends of the horizontal slots 56, and while the slots 52 in the portion 50 and the vertical portions 62 of the L-shaped slots 61 are in register, the radially extending pins 53 secured to the spindle 46 may be positioned in the bottoms of the slots 52 and horizontal portions of the slots 61, after which the sleeve 54 may be released and the sleeve rotated under tension of the spring 58 to bring the closed ends of the slots 61 against the pins 53 and the overhanging portions 54a of the sleeve 54 across the slots 52, thereby closing the upper ends of the slots 52 against the removal of the pins 53 and preventing the longitudinal displacement of the spindle 46 with respect to the body portion 21.

For adjusting the bars 29 and integral cam faces 30 thereof longitudinally of the cams 27 in a manner to move the stones 22 and stone holders 23 outwardly or radially with respect to the body member 21, a novel adjusting means, designated as a whole by the numeral 63, is provided, see particularly Figs. 1 and 10 to 15 inclusive.

This adjusting means 63 is held in spaced relation with respect to the grinding tool 20 by means of a spacer shown in the present instance as a tube 64 surrounding the rod 38 and positioned within the hollow portion of the spindle 46, the lower end of the tube being seated in a cup-like depression 65, Fig. 3, formed in the body member 21 adjacent the bottom of the socket 51, while the upper end

of the tube is adapted to seat in an inverted cup-like depression 66 formed in the under-side of a thrust plate 67 having an opening therein adjacent its central portion through which the rod 38 extends, and thence upwardly through an opening formed in a second thrust plate 68 having a cup-like depression 69 formed in its upper side adapted to receive a spherical portion 70 of a head 71 formed on the upper end of the rod 38. The spindle 46 is provided adjacent its upper end portion with a pair of diametrically disposed longitudinally extending slots 72 through which the ends of the thrust plates 67 and 68 extend, the said plates being adapted to engage at their outer ends one of the rings of anti-friction thrust bearings 73 and 74, surrounding the spindle 46, while the other or opposing rings of the respective thrust bearings 73 and 74 are seated in the bottom portions of oppositely disposed relatively adjustable non-rotatable socket members 75 and 76, respectively, the said socket members having formed in the bottom portions thereof the openings 77 and 78, respectively, for the passage of the spindle 46 therethrough.

It will be observed from the foregoing description that the spindle 46 may be rotated carrying with it the thrust plates 67 and 68 together with one of the rings of the bearings 73 and 74, while the other rings of the bearings and socket members 75 and 76 remain stationary or non-rotatable.

For securing the socket members 75 and 76 against rotation, a holding member 79 is provided with a laterally extending arm 80 having a roller 81 secured to its outer or free end, the said roller being adapted to be engaged between the legs of a vertically extending channel member 82 secured preferably to the frame or some fixed part of the machine containing the mechanism for reciprocating and rotating the spindle 46 and tool 20, thus permitting the spindle, tool and adjusting means 63 to be reciprocated and at the same time securing the holding member 79 against rotation.

Formed on the upper side of the member 79 is a boss 83 over which the socket member 75 is adapted to fit to prevent lateral or transverse movement of the said socket member with respect to the holding member 79, and formed in the lower edge of the socket member 75 is a notch or key-way 84, Fig. 15, adapted to receive a lug or key 85 of corresponding dimensions formed on the periphery of the boss 83, thereby securing the socket member 75 against annular movement with respect to the holding member 79.

For securing the socket member 75 snugly over the boss 83 and against the upper face of the holding member 79, a plurality of pins or bolts 86 having shank portions 87 are annularly spaced around the inner wall of the socket member 75 in a manner to extend

through openings formed in the upper end or bottom portion of the inverted socket member 75 and through apertures formed in the holding member 79, the lower end of the shank portion 87 being provided with threads adapted to receive nuts 88. The upper ends of the pins or bolts 86 are formed with relatively large upwardly extending head portions 89, providing shoulders 90 adapted to engage the top surface of the socket member 75 in a manner to enable the nuts 88 to draw the socket member 75 snugly against the holding member 79. The head portions 89 are adapted to be slidably received in registering apertures formed in the bottom portion of the socket member 76 in a manner to secure the member 76 against rotation and at the same time permit of relative longitudinal or vertical adjustment of the member 76 with respect to the socket member 75.

For moving the socket member 76 and rod 38 longitudinally with respect to the socket member 75, it will be noted by reference to Fig. 10 that the respective socket members 75 and 76 are provided on their outer annular faces with screw threads of relatively different pitch, for example, the socket member 75 may have ten threads to the inch, and the socket member 76 may be provided with sixteen threads to the inch. Surrounding the socket members is an adjusting sleeve 91 having screw threads of relatively different pitch formed therein adapted for engagement with the threads of corresponding pitch formed on the respective socket members 75 and 76, for example, the threads formed in the lower end portion of the sleeve 91 are adapted to engage the screw threads on the socket member 75, and the threads formed in the upper end portion of the sleeve 91 are adapted to engage the screw threads formed on the socket member 76.

For convenience and certainty of rotation, the adjusting sleeve 91 may be knurled as indicated, and it will be noted that if the sleeve is rotated to the right as viewed in Figs. 10 and 11 or counter-clockwise, as viewed in Figs. 12 and 13, assuming that the threads on the sleeve are of right hand formation, the sleeve 91 will move longitudinally and upwardly with respect to the socket member 75, and although the sleeve has screw threaded engagement with the socket member 76, by reason of the difference in the pitch of the threads formed on the respective sockets, the socket member 76 will be moved longitudinally and upwardly with respect to the socket member 75, although at a reduced speed as compared with that of the sleeve 91. This movement of the sleeve 76, it will be noted, is transmitted to the adjusting rod 38 through the thrust bearing 74 and adjusting rod thrust plate 63, thereby causing an upward longitudinal movement of the rod 38, spider member 33 and adjusting bars 29, the latter,

by reason of their integral cam faces 30 engaging the cams 27 formed on the body member 21, being also moved outwardly in a manner to force the stones 22 and stone holders 23 radially with respect to the body member 21 against the action of the resilient flexible bands or tension springs 43 for the purpose of maintaining the grinding stones 22 in contact with the surfaces to be operated upon.

10 For limiting the movement of the adjusting sleeve 91 in a manner to determine the amount of material to be removed by the stones 22, a screw threaded ring 92 is mounted on the socket member 75 in threaded engagement therewith, and has provided on its upper side a lug or stop 93 adapted to be engaged by a depending lug or finger 94 formed on the lower end of the adjusting sleeve 91 when the sleeve has reached the desired limit 15 of adjustment. For locking the ring 92 in adjusted position, a jam nut or ring 95 is mounted on the socket member 75 in screw threaded engagement therewith and may be forced against the under or lower side of the ring 92 after the lug 93 thereon has been positioned, as desired, with respect to the lug or finger 94 formed on the adjusting sleeve 91.

In the operation of the device, the grinding tool may be positioned, for example, 20 within the bore of an engine cylinder to be ground, and the grinding stones 22 moved radially of the body member 21 by the rotation of the adjusting sleeve 91 until they contact with the walls of the cylinder, after 25 which the ring 92 may be rotated in a manner to move the lug 93 away from the lug 94 a sufficient distance to permit of the desired further radial adjustment of the stones for 30 removing a predetermined amount of material from the inner surface of the cylinder wall, and the ring 92 and lug 93 may then be secured in such position by means of the jam ring 95. The mechanism for rotating 35 and reciprocating the spindle 46 and tool 20 may then be started and as the surface of the cylinder wall is ground away, the stones 22 may be moved outwardly to retain grinding contact with the surface operated upon by 40 rotating the adjusting sleeve 91 as heretofore described until the lug 94 of the adjusting sleeve engages the lug 93 of the sleeve or ring 92, at which time the desired amount of material will have been removed from the wall 45 of the cylinder.

It will be noted by reference to the drawings, particularly Figs. 3 and 10, that by reason of the clearance provided between various portions of the device, and the manner of 50 connecting the rod 38 to the spider 33 and to the adjusting rod thrust plate 68, and the manner of positioning the spacing tube 64 with reference to the body member 21 and spacing tube thrust plate 67, a degree of flexibility in the device is obtained which enables 55

the proper centering and operation of the grinding tool 20 within the cylinder bore.

Obviously, the present invention is not limited to the precise construction and arrangement shown and described, as the same may be variously modified. Moreover, all the features of the invention need not be used conjointly as the same may be used to advantage in variously different combinations and sub-combinations.

What I claim as my invention and desire to secure by Letters Patent is:

1. A device of the class described comprising, in combination, a body member provided with a plurality of circumferentially spaced longitudinal radially formed grooves, cams mounted at the respective bottoms of each of said grooves, a plurality of radially movable abrading stones mounted in the grooves on said body member and carried by said cams but being formed separately therefrom, means movable longitudinally with respect to said body member for operating said cams for moving said stones radially with respect to said body member, means for holding the abrading stones in contact with the supporting surfaces of said cam members, and means for adjusting said longitudinally movable means with respect to said cams.

2. A device of the class described comprising, in combination, a body member provided with a plurality of circumferentially spaced longitudinal radially formed grooves, cams formed at the respective bottoms of each of said grooves, a plurality of annularly spaced radially movable abrading stones mounted in the grooves on said body member and carried by said cams but being formed separately therefrom, longitudinally movable means positioned between said cams and stones and co-operable with said cams for moving said stones radially with respect to said body member, means for holding the abrading stones in contact with the supporting surfaces of said cam members, and adjustable means for positioning said longitudinally movable means with respect to said cams.

3. A device of the class described comprising, in combination, a body member provided with a plurality of circumferentially spaced longitudinal radially formed grooves, cams formed at the respective bottoms of each of said grooves, a plurality of annularly spaced radially movable abrading stones mounted in the grooves on said body member, a plurality of longitudinally movable stone adjusting bars in said grooves co-operable with said cams for moving said stones outwardly with respect to said body member, means for moving said stones inwardly with respect to said body member and for holding them in contact with said stone adjusting bars, a driving spindle connected to said body member, and rotatable longitudinally 130

adjustable means for moving said bars longitudinally of said cams.

4. A device of the class described comprising, in combination, a body member provided with a plurality of circumferentially spaced longitudinal radially formed grooves, cams formed at the respective bottoms of each of said grooves adjacent the ends thereof, a plurality of annularly spaced radially movable abrading stones mounted in the grooves on said body member, a plurality of longitudinally and transversely movable stone adjusting bars carrying wedge-shaped portions positioned between said cams and stones and co-operable therewith for moving said stones outwardly with respect to said body member, resilient means for moving said stones inwardly with respect to said body member, a driving spindle releasably connected to said body member, and rotatable longitudinally adjustable means associated with said spindle for moving said bars longitudinally of said cams in a manner to move said bars laterally and said stones outwardly with respect to said body member.

5. A device of the class described comprising, in combination, a body member provided with a plurality of circumferentially spaced longitudinal radially formed grooves, cams formed at the bottoms of said grooves adjacent the ends thereof, a plurality of radially movable abrading stones mounted in said body member, a plurality of longitudinally movable adjusting bars positioned between said cams and stones and having inclined cam faces adjacent their end portions adapted to engage said cams, means for moving said stones inwardly with respect to said body member, a driving spindle, a releasable coupling for connecting said body member to said spindle in a manner to be rotated therewith, and rotatable longitudinally adjustable means associated with said spindle for moving said cam faces along said cams in a manner to move said bars laterally and said stones outwardly with respect to said body member.

6. A device of the class described comprising, in combination, a body member, cams formed thereon adjacent the ends thereof, a plurality of radially movable abrading stones having holders therefor mounted in said body member, a plurality of longitudinally movable adjusting bars positioned between said cams and holders and having inclined cam faces formed thereon adjacent their end portions adapted to engage said cams, resilient means for moving said holders inwardly with respect to said body member, a rotatable driving spindle, a releasable coupling for connecting said body member to said spindle in a manner to be rotated therewith, and rotatable longitudinally adjustable means associated with said spindle for moving said cam faces longitudinally along said

cams in a manner to move said bars laterally and said holders and stones outwardly with respect to said body member.

7. A device of the class described comprising, in combination, a body member, cams formed thereon adjacent the ends thereof, a plurality of radially movable abrading stones mounted in said body member, a plurality of longitudinally movable adjusting bars positioned between said cams and said stones and having inclined cam surfaces formed thereon adjacent their end portions adapted to engage said cams, means on said body member for holding said stones against longitudinal movement with respect thereto, resilient means for moving said stones inwardly with respect to said body member, a rotatable longitudinally reciprocable driving spindle, a releasable coupling for connecting said body member to said spindle in a manner to be rotated and reciprocated therewith, and rotatable longitudinally adjustable means associated with said spindle for moving said cam surfaces longitudinally along said cams in a manner to move said bars laterally and said stones outwardly with respect to said body member.

8. A device of the class described comprising, in combination, a body member, cams formed thereon adjacent the ends thereof, a plurality of radially movable abrading stones having holders therefor mounted in said body member, a plurality of longitudinally movable adjusting bars positioned between said cams and holders and having inclined cam portions formed thereon adjacent the ends thereof adapted to engage said cams, means formed on said body member adjacent the ends thereof for securing said stones and holders against longitudinal movement with respect to said body member, resilient means for moving said stones and holders inwardly with respect to said body member, a vertically reciprocable and rotatable driving spindle, a releasable coupling for connecting said body member to said spindle in a manner to be rotated and reciprocated therewith, and rotatable longitudinally adjustable means associated with said spindle for moving said adjusting bars and cam portions longitudinally along said cams in a manner to move said bars laterally and said holders and stones outwardly with respect to said body member.

9. A device of the class described comprising, in combination, a body member provided with a plurality of circumferentially spaced longitudinal radially formed grooves, cams formed at the respective bottoms of each of said grooves adjacent the ends thereof, a plurality of radially movable abrading stones having holders therefor mounted in said grooves in the body member, a plurality of longitudinally movable adjusting bars positioned between said cams and holders and

having inclined cam faces formed thereon adjacent the ends thereof adapted to engage and co-operate with said cams, means formed on said member adjacent the ends thereof and co-operable with means on the respective ends of said holders for securing said stones and holders against longitudinal movement with respect to said body member, resilient means for moving said stones and 5 holders inwardly with respect to said body member, a vertically reciprocable and rotatable hollow driving spindle, longitudinally extending means positioned within the hollow portion of said spindle means for connecting said body member to said spindle in a manner to be rotated and reciprocated therewith, and rotatable longitudinally adjustable means surrounding said spindle and connected with said means positioned within 10 the hollow portion of said spindle for moving said adjusting bars and cam faces longitudinally along said cams in a manner therewith and move said bars laterally and said holders and stones outwardly with respect to 15 said body member.

10. A device of the class described comprising, in combination, a body member having a longitudinally extending opening therein and cams formed thereon, a plurality of radially movable abrading stones mounted in said member, a plurality of stone adjusting bars positioned between said body member and stones and having cam surfaces formed thereon co-operable with said cams 20 in a manner to provide supports for said stones throughout their entire length, a spider member mounted in said body member and having a plurality of radially extending arms engageable with said bars, a rotatable vertical reciprocable hollow driving spindle, a releasable coupling for connecting said body member to said spindle in a manner to be rotated and reciprocated therewith, a rod positioned in the hollow portion of said spindle and the opening formed in said body member, said rod being connected to said spider member, and rotatable longitudinally movable means operatively connected to said rod for adjusting said bars longitudinally 25 of said cams.

11. A device of the class described comprising, in combination, a body member having a longitudinally extending opening therein and cams formed thereon adjacent the ends thereof, a plurality of annularly spaced radially movable abrading stones having holders therefor mounted in said body member, a plurality of longitudinally adjustable stone adjusting bars positioned 30 between said body member and holders and having cam surfaces formed thereon adjacent their end portions and co-operable with said cams in a manner to provide supports for said stones and holders throughout their entire length regardless of the adjustment of

said bars with respect to said cams, a spider member slidably mounted in said body member and having a plurality of annularly spaced radially extending arms engageable with said bars, a rotatable vertically reciprocable hollow spindle, means mounted adjacent the upper end of said body member for connecting the body member to said spindle in a manner to be rotated and reciprocated therewith, a rod positioned in the hollow portion of said spindle and the opening formed in said body member, said rod being connected at its lower end to said spider member, rotatable longitudinally movable means surrounding said spindle and operatively connected therewith and with said rod for adjusting said bars longitudinally of said cams in one direction, and means for moving said spider and bars in the opposite direction. 35

12. A device of the class described comprising, in combination, a body member provided with a plurality of circumferentially spaced longitudinal radially formed grooves having cams formed in the bottoms thereof, a plurality of radially movable abrading stones and holders therefor mounted in said member, adjusting bars co-operable with said cams for moving said stones outwardly with respect to said members, and means for adjusting said bars with respect to said cams, said means including a rod operatively connected to said bars, a plurality of relatively movable adjusting members operatively related to said body member and said rod respectively, and means operatively connected to said adjusting members for moving said members with respect to each other in a manner to move said rod and bars with respect to said body member and cams in said grooves. 40

13. A device of the class described comprising, in combination, a body member having cams formed thereon, a plurality of radially movable abrading stones and holders therefor mounted in said member, adjusting bars engageable with said cams and holders for moving said stones outwardly with respect to said member, and means for adjusting said bars with respect to said cams, said means including a rod operatively connected to said bars, a plurality of longitudinally movable relatively adjustable socket members operatively related to said body member and said rod, respectively, and a sleeve having screw threaded engagement with said socket members for adjusting said members with respect to each other to move said rods and bars with respect to said cams in a manner to cause said holders and stones to be moved outwardly with respect to said body 45 member. 110

14. A device of the class described comprising, in combination, a body member having cams formed thereon, a plurality of radially movable abrading stones and holders there- 50

for mounted in said member, adjusting bars engageable with said cams and holders for moving said stones outwardly with respect to said member, and means for adjusting said bars with respect to said cams, said means including a rod operatively connected to said bars, a plurality of longitudinally movable relatively adjustable socket members operatively related to said body member and said rod, respectively, the respective socket members having screw threads of relatively different pitch formed thereon, and a rotatable adjusting sleeve surrounding said socket members and having screw threads of relatively different pitch formed therein engageable with the threads of corresponding pitch formed on the respective socket members for relatively adjusting said socket members to move said rod and bars with respect to said cams in a manner to cause said holders and stones to be moved outwardly with respect to said body member.

15. A device of the class described comprising, in combination, a body member having cams formed thereon, a plurality of radially movable abrading stones and holders therefor mounted in said member, adjusting bars engageable with said cams and holders, means for adjusting said bars with respect to said cams in a manner to move said stones outwardly with respect to said member, said means including an adjusting rod operatively connected to said bars, a plurality of relatively adjustable socket members, thrust bearings positioned in the respective socket members, means for positioning one of said bearings with respect to said body member, means for connecting the other of said bearings to said rod, and a rotatable sleeve operatively connected to said socket members for relatively adjusting the members, rod and bars with respect to said cams in a manner to cause said stones to be moved outwardly with respect to said body member.

16. A device of the class described comprising, in combination, a body member having cams formed thereon, a plurality of radially movable abrading stones and holders therefor mounted in said member, adjusting bars engageable with said cams and holders, means for adjusting said bars with respect to said cams in a manner to move said stones outwardly with respect to said member, said means including an adjusting rod operatively connected to said bars, a plurality of relatively adjustable screw threaded socket members, thrust bearings positioned in the respective socket members, means for spacing one of said bearings and socket members with respect to said body member, means for connecting the other of said bearings to said rod, a rotatable screw threaded sleeve surrounding and having threaded engagement with said socket members for relatively adjusting said members, rod and bars with re-

spect to said cams in a manner to cause said stones to be moved outwardly with respect to said body member, and adjustable means for limiting the rotation of said sleeve.

17. A device of the class described comprising, in combination, a body member having cams formed thereon, a plurality of radially movable abrading stones and holders therefor mounted in said member, adjusting bars engageable with said cams and holders, means for adjusting said bars with respect to said cams in a manner to move said stones outwardly with respect to said member, said means including an adjusting rod operatively connected to said bars, a plurality of relatively adjustable non-rotatable oppositely disposed screw threaded socket members, means for securing said members against rotation, anti-friction thrust bearings positioned in the respective socket members, means for spacing one of said bearings and socket members with respect to said body member, means for connecting the other of said bearings to said rod, a rotatable screw threaded sleeve surrounding and having threaded engagement with said socket members for relatively adjusting said socket members, rod and bars with respect to said cams in a manner to cause said stones to be moved outwardly with respect to said body member, adjustable means for limiting the rotation of said sleeve, and means for securing said adjustable means in adjusted position.

18. A device of the class described comprising, in combination, a body member having cams formed thereon, a plurality of radially movable abrading stones and holders therefor mounted in said member, adjusting bars engageable with said cams and holders, a rotatable hollow spindle connected to said body member and having diametrically disposed longitudinally extending slots formed therein, means for adjusting said bars with respect to said cams in a manner to move said stones outwardly with respect to said member, said means including an adjusting rod positioned in the hollow portion of said spindle and operatively connected to said bars, a plurality of relatively adjustable non-rotatable socket members surrounding said spindle, means for securing said members against rotation, thrust bearings positioned in the respective socket members and surrounding said spindle, a thrust plate extending through the slots formed in said spindle and operatively related to one of said thrust bearings, means within the hollow portion of said spindle for positioning said plate with respect to said body member, a second thrust plate extending through said slots and operatively related to the other of said bearings and to said adjusting rod, a rotatable sleeve having screw threaded engagement with said socket members for adjusting one of said members, said rod and bars with respect to

the other of said socket members and said cams, means mounted on one of said socket members and adjustably thereon for limiting the rotation of said sleeve, and means 5 for securing said adjustable means in adjusted position.

19. A device of the class described including adjusting means comprising a plurality of relatively movable non-rotatable socket 10 members having screw threads of relatively different pitch formed on the respective members, means for securing said members against rotation, a thrust bearing positioned in one of said members, an adjusting rod 15 operatively related to said bearing, and a rotatable adjusting sleeve surrounding said members and having screw threads of relatively different pitch formed therein adapted for engagement with the threads of corresponding 20 pitch formed on the respective socket members for adjusting one of said members, said thrust bearing and rod with respect to the other of said socket members.

20. A device of the class described including 25 adjusting means comprising, a plurality of relatively movable non-rotatable socket members having screw threads of relatively different pitch formed on the respective members, means for securing said members 30 against rotation, a thrust bearing positioned in one of said members, an adjusting rod operatively related to said bearing, a rotatable adjusting sleeve surrounding said members and having screw threads of relatively 35 different pitch formed therein adapted for engagement with the threads of corresponding pitch formed on the respective socket members for adjusting one of said members, said thrust bearing and rod with respect to 40 the other of said socket members, adjustable means for limiting the rotation of said sleeve, and means for securing said adjustable means in adjusted position.

21. A device of the class described including 45 adjusting means comprising a plurality of relatively movable, non-rotatable socket members, means for securing said members against rotation, a thrust bearing positioned in one of said members, an adjusting rod 50 operatively related to said bearing, a rotatable adjusting sleeve having screw threaded engagement with the other of said members and being operatively related to said one of said members for adjusting said last mentioned member, said thrust bearing and adjusting rod with respect to said other of 55 said members.

In testimony whereof I have signed my 60 name to this specification, on this 30th day of January A. D. 1928.

ARTHUR M. JOHNSON.
